UNITED STATES PATENT OFFICE.

WARREN S. BELDING, OF CHICAGO, ILLINOIS, ASSIGNOR TO THE BELDING MOTOR AND MANUFACTURING COMPANY, OF SAME PLACE.

ELECTRIC MOTOR.

SPECIFICATION forming part of Letters Patent No. 404,067, dated May 28, 1889.

Application filed November 15, 1887. Serial No. 255,192. (No model.)

To all whom it may concern:

Be it known that I, WARREN S. BELDING, a citizen of the United States, residing at Chicago, in the county of Cook and State of Illinois, have invented certain new and useful Improvements in Electric Motors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention embraces novel features, as hereinafter described, and particularly pointed out in the appended claims.

In the accompanying drawings, Figure 1 is a front elevation. Fig. 2 is a rear elevation. 20 Fig. 3 is a side elevation looking from the left toward Fig. 2. Fig. 4 is a vertical section in line *x x* of Fig. 1. Fig. 5 is a section in line *y y* of Fig. 3. Fig. 6 is a detail view of the armature. Fig. 7 is a detail view of one of the field-magnets. Figs. 8 and 9 are detail 25 views of the commutator. Fig. 10 is a detail view showing the manner of combining and connecting the brushes, commutator, and armature. Fig. 11 is a detail of the rack which 30 supports the brushes. Fig. 12 is a detail of a commutator the plates of which are in multiples of three.

A is the shaft supporting the armatures and commutator. One end of said shaft is 35 supported in a bearing, A', in the disk A², and the other end is supported in a bearing, A³, in a bracket, A⁴, extending outwardly from the disk A⁵, the opening *a*⁵ in the disk A⁵ being large enough to receive said shaft and 40 commutator without contact.

B and C are the armatures. The armature B is applied to the outer ends of the arms of a spider, B', whose hub is fixed around the shaft A. Said armature has four straight laterally-compressed cores, B², which occupy the 45 space between the arms of the spider B' and terminate in the expanded prolongations or poles B³, resting against the ends of the spider-arms. Screws B⁴ pass through said poles into 50 the spider-arms and join the latter to the former. At least two opposite poles, B³, are cut

transversely to the plane of the armature and directly in line with the axis of the adjacent spider-arm, so that the "ring" of the armature may be separated into two or more pieces 55 before winding the helix upon the cores.

The armature C is a duplicate of B, but is turned twenty-two and one-half degrees on the shaft A, so as to make its poles alternate with the poles of the armature B, and said 60 armatures are set apart a sufficient distance to permit the interposition of the middle branch of the pole-pieces of the field-magnets, to be hereinafter described.

D is the commutator, composed of the well-known insulation-core D' and plates D². Said plates are eight in number—one for each coil of the two armatures. The opposite of said plates are joined to each other electrically by means of wires D³, thus making four groups 70 of two of said plates. A brush in contact with any one plate will then be in electrical communication with the other plate of the same group.

The end of the commutator may have the 75 annular recess D⁴ around the shaft A for the reception of the wires D³, and when said wires are in place in said recess the latter may be poured full of melted wax or other insulating material. Said wires are then secure against 80 injury when the motor is being handled and are held against movement in response to centrifugal force while the motor is in motion. I prefer to secure said wires D³ to the commutator-plates by forming recesses or slots d 85 in the ends of the commutator-plates and setting the ends of the wires into said recesses or slots.

Two brushes, E E', set a quarter of the circumference of the commutator D from each other, are mounted on arms E² E'², respectively. Said arms are secured in non-conducting bushings E⁴ E'⁴ in a rack, E⁶, journaled on the hollow spindle a⁴, extending outwardly from the bracket A⁴. The hub of said rack is cut away 95 to form a notch, a⁵, and a screw, a⁶, set into the spindle a⁴ in said notch, allows said rack to make a quarter of a turn on said spindle and no more, whereby the brushes may be carried a quarter of a turn on the commutator 100 and put into electric communication with another group of plates, D².

For convenience in description, the plates D^2 are numbered in series from 1 to 8, inclusive, and the cores of each armature are numbered in series from 1 to 4, inclusive.

5 The wire-connections between the commutator and the armatures will be understood by an examination of Fig. 10. Said figure shows one armature and the inner end of the commutator, the latter being seen through the armature. The helix-wire G leaves the binding-screw on plate 1 of the commutator and passes over the nearer end of the core 1 and around the latter often enough to complete the helix, and thence to the binding-screw on plate 3. The wire G' leaves the screw 3 and passes around the core 2 in the same manner as stated of the wire G , and is bound beneath the screw on plate 5. The wire G^2 extends in the same manner from the screw on plate 5 to the screw on plate 7 and the wire G^3 extends in the same manner from the screw on the plate 7 to that on plate 1. Instead of binding each end of these wires under said screws the adjacent ends may be united and only one bound by the screw. It is also to be noted that the ends of the connecting-wires D^3 may be joined to the ends of the helix-wires, as shown in Fig. 10, instead of being attached directly to the plates D^2 , the result being the same—to wit, making groups of said plates. The helix-wires are applied to the other armature in the same manner as shown in Fig. 10, the ends being bound to the plates 2, 4, 6, and 8.

35 Supposing the current to be coming from a generator to the brush resting on plate 1, then said current will divide, and a portion go through the wire G^3 to the plate 7, and out through the brush on said plate, while another portion of the current goes through the wire G to the plate 3, and thence through the connecting-wire D^3 to the plate 7 and the brush resting on said plate. The remainder of said current goes from the plate 1 over the adjacent connecting-wire D^3 to the plate 5, the companion of the group, whence it divides and a portion goes through the wire G^2 , the plate 7, and the brush on said plate. The remainder goes through the wires G' and D^3 and the plate 7 and its brush. Under this arrangement of the current the armature is quadrupolar, the adjacent poles of the cores 1 and 4 constituting a north pole, and the adjacent ends of the cores 2 and 3 constituting a north pole, while the intermediate ends of said cores constitute south poles. One-fourth of a rotation of the armatures and the commutator or the rack supporting the brushes reverses the direction of the current over all the wires in the armatures, and as a consequence also reverses the polarity of each of the poles.

65 An eighth of a rotation of the armatures and commutator, or of the rack holding the brushes, takes one armature entirely out of and places the other into the circuit. Thus, when the motor is in operation, one armature

is first alone in circuit and its poles are of certain polarities; then the other armature is alone in circuit and its poles are of certain polarities; then the first armature is again alone in circuit with the polarities of its poles reversed; the second armature is again alone in circuit with the polarities of its poles reversed, and so on continuously. A lever, E^7 , may be applied to the rack E^6 , by which the latter may be shifted.

7c H H are the field-magnets, terminating in the pole-pieces $H' H' H' H'$. Each of said pole-pieces has three laterally-compressed branches, H^2 , one extending over and almost into contact with the outer side of each armature toward the shaft A, and the other extending between the two armatures and almost into contact with them. By compressing the armatures, and thus extending the arms of the pole-pieces of the field-magnets over the sides of the armatures, a larger portion of said pole-pieces is brought into proximity to the armatures, and the attraction and repulsion, acting between said pole-pieces and the armatures, are thereby strengthened. The disks A^2 and A^5 and the pole-pieces H' are joined by screws H^3 , so that said pole-pieces and disks together constitute the frame 95 of the motor.

80 I is a bridge extending from one of the upper pole-pieces to the other and supporting the insulated binding-posts $I' I'$.

85 J and J' are the wires leading from the generator to the binding-posts, and K K are wires leading from one binding-post and so connected with the field-magnets as to make the latter alternate in polarity, and leading thence to one of the brushes. From the opposite brush a wire, L, leads to the other binding-post.

90 The coils of the armature and the commutator plates may be increased in number in multiples of two or three, and the poles of the field-magnets are always to be multiples of the same numbers, equal to or less than the total number of armature-coils or commutator-plates, and so long as the total number of armature-coils or commutator-plates is a multiple of two and not also of three the commutator-plates are to be connected in groups of two, and if the said plates are multiples of three and not also of two the said plates are to be connected in groups of three, while if 110 said plates are multiples of both two and three said plates may be connected either in groups of two or three.

115 Fig. 12 illustrates the commutator for a single armature, B or C, in which commutator 120 the plates are connected in groups of three. The number of said plates is six, the first multiple of three, and the number of poles in the armature is the same. The connections of the plates 1 3 5 lead to one set of armature-poles, and each of said three plates is joined to the other two by two direct wires, D^8 . The connections of the plates 2 4 6 lead to the other set of armature-holes, and

each of said three plates is joined to the other two by two direct wires, D³. It is to be noted that the group could be formed with one wire, D³, as a single wire may lead 5 from plate 1 to plate 3 and thence to plate 5; but by using two direct wires the resistance to the current is decreased. When the commutator is thus wired, the two brushes will communicate with the six plates and through the 10 latter with the six poles, and said brushes may be placed upon adjoining plates, as 1 and 6, or upon opposite plates, as 1 and 4. In either case the brushes will be in communication with groups of commutator-plates leading 15 to armature-poles of opposite polarity.

When a single armature is to be used, it is wired to the commutator-plates in the manner shown of either the armature B or C, illustrated in the drawings, and said armatures 20 are broadened to cover the spaces occupied by the alternate plates in the motor having the two armatures.

By grouping the commutator-plates as described it is possible to change the communication of the brushes from one set of commutator-plates to the opposite set of said plates and reverse the current polarity and motion without turning the brushes half-way round the commutator. On the contrary, as I 25 have shown, the current and the motion may be reversed in my motor by a quarter-turn or less of the brushes. The advantage of this consists in the fact that it is easy to provide for a quarter-turn or less of the brushes, while 30 it is very difficult to make provision for a full half-turn.

I claim as my invention—

1. A commutator having a series of insulated plates, D², an annular recess, D⁴, and 40 wires D³ in said recess and connecting said plates into groups, substantially as shown and described.

2. A commutator having a series of insulated plates, D², an annular recess, D⁴, wires 45 D³ in said recess and connecting said plates into groups, and said recess D⁴ filled with wax or other insulating material, substantially as shown, and for the purposes described.

3. A commutator having a series of insulated plates, D², an annular recess, D⁴, and 50 wires D³ in said recess, said commutator-plates having recesses or slots d at their ends, and the ends of said wires being secured in said

recesses or slots d, substantially as shown and described.

4. A commutator having a series of insulated plates, D², an annular recess, D⁴, and wires D³ in said recess, said commutator-plates having recesses or slots d at their ends, and said wires being secured in said recesses or 55 slots d, and said recess D⁴ being filled with wax or other insulating material, substantially as shown, and for the purposes described.

5. In an electric motor, a plurality of armature-sections connected with the plates of the 60 commutator, and a commutator having an annular recess, D⁴, and wires D³ in said recess and connecting the commutator-sections into groups, whereby each armature-section is brought into communication with each brush 70 more than once during each rotation of the commutator, substantially as shown and described.

6. In an electric motor, a plurality of armature-sections connected with the plates of the 75 commutator and a commutator having an annular recess, D⁴, and wires D³, and an insulating material in said recess, said wires connecting the commutator-sections into groups, whereby each armature-section is brought 80 into communication with each brush more than once during each rotation of the commutator, substantially as shown and described.

7. In an electric motor, a plurality of armature-sections connected in parallel, a commutator having a recess, D⁴, wires D³ in said recess and connecting the commutator-plates into groups, and two brushes held in contact with commutator-plates whose connections lead to armature-poles of opposite polarity, 90 substantially as shown and described.

8. In an electric motor, a plurality of armature-sections connected in parallel, a commutator having a recess, D⁴, wires D³, and an insulating material in said recess, said wires 95 connecting the commutator-plates into groups, and two brushes held in contact with commutator-plates whose connections lead to armature-poles of opposite polarity, substantially as shown and described.

In testimony whereof I affix my signature in presence of two witnesses.

WARREN S. BELDING.
